BATTERY PATCH

Application filed February 27, 1929. Serial No. 343,172.

The object of this invention is to provide a patch device for application to a battery or magazine of a loom whereby, when the edge of the battery or magazine side plate 5 has been worn away or broken so that it does not properly hold a bobbin support, the bobbin support may be secured in place and effectually held without requiring the discarding of the magazine side plate and the 10 provision of a new side plate, the expense of maintenance and operation being thereby very appreciably reduced.

In the accompanying drawing:

Figure 1 is an elevation of a portion of 15 a magazine side plate showing the bobbin support in position with my improved patch applied, the view looking at the inner face of the side plate,

Fig. 2 is a similar view looking at the 20 outer side of the plate,

Fig. 3 is a transverse section on the line 3—3 of Fig. 2, and

Fig. 4 is a detail perspective view of the 25 patch.

The reference numeral 1 indicates a portion of the side plate of a bobbin magazine and the numeral 2 indicates a portion of an annular flange on the inner face of said plate which aids in supporting the bobbins 30 and directing them to the stop device 3 and the cooperating support 4. The bobbin support 4 is yieldably held in the position shown in Fig. 1 by a spring 5 coiled about the supporting bolt 6 and acting upon the 35 support to yieldably hold it in an upper position. The details of the bobbin support form no part of my present invention and further description of the same is deemed unnecessary, it being noted that the supporting 40 bolt 6 passes through an eye or bearing 7 provided therefor on the edge of the side plate 1 immediately under the flange 2. The side plate is also provided on its outer face with a forked lug 8 which provides 45 a support for a part of the operating mechanism. The eye or bearing which supports the bolt 6 is subjected to severe wear when the machine is operated continuously for any considerable period and eventually the 50 eye breaks away or wears out in its lower

portion so that it fails to properly hold the bolt 6, the bolt being held in place by a nut 9 mounted on its outer end and turned home against the end of the eye, as will be understood. Heretofore, when the eye 55 broke away or wore out in its under side and formed an opening or slot, indicated at 10, it necessitated the discarding of the side plate 1 and the provision of an entirely new side plate which is obviously expensive. 60 To overcome this difficulty, I have devised the patch shown most clearly in Figs. 2, 3 and 4 which consists of a casting 11 of an approximately diamond outline having an eye or bearing 12 formed in its lower central portion having an opening 13 to receive the outer end of the bolt 6 and an enlarged recess or chamber 14 concentric with said opening to fit around the end of the eye 7, as clearly shown in Fig. 3. The lower edge 65 of the casting 11 is properly shaped to conform to the outer flange 15 formed on the side plate 1 so that it may be easily fitted in proper position with the eye 12 properly centered relative to the eye or bearing 7 and the outer surface of the casting immediately around the opening 13 is 70 smooth and flat so that the nut 9 may be turned home against the same to secure the casting in position. In the upper edge of 75 the casting is a transverse notch 16 which engages the lower edge of the lug 8, as shown in Fig. 2, whereby the placing of the casting in its proper position is facilitated and the holding of the same after it is 80 placed is made certain. It will be observed that the patch extends over the broken eye or bearing of the magazine side plate so that it is reinforced and strengthened and the bobbin support effectually secured in its 85 operative position without requiring the provision of a new side plate. It may be that in the course of time the patch will be broken or worn away but in such event a second patch may be substituted therefor at 90 a very considerable saving over the cost of providing an entirely new side plate and it should be observed that the patch presents a greater body of metal below the bolt 6 than does the original eye or bearing on the 95

battery side plate so that the bolt and the bobbin support are actually more firmly secured by the patch than when originally assembled. The form of the patch and its engagement with the lug 8 very effectually resists and overcomes any tendency of the patch to rock and thereby loosen or release the bolt 6 and the bobbin support.

Having thus described the invention, I claim:

- 10 1. A patch device for the purpose set forth consisting of a tapered elongated body having end portions formed to rest on the flanges of a battery plate and having an eye in its lower edge between its end portions to fit around and house the end of the bobbin support bearing of the battery plate and the end of the holding member of the bobbin support.
- 15 2. A patch device for the purpose set forth comprising a body having a lug-engaging notch in its upper edge and having its end portions formed to rest on the flange of a battery plate and provided in its lower edge portion with a bearing eye to house the end of the bearing for a bobbin support.
